DISHWASHING MACHINE

James O. McMillan, Wichita, Kans., assignor to
Frank J. Ablah, Wichita, Kans.

Application December 11, 1948, Serial No. 64,750

11 Claims. (Cl. 134—191)

1

This invention relates in general to dishwashing machines and in particular to a dishwasher adapted to receive a basket of soiled dishes, and which employs a hydro-actuated rotating jet member, a detergent supply and automatic control of liquid and detergent supply.

Many devices have been developed in the art of washing dishes and yet there cannot be found in the field a dishwasher which is compact, easy to install and service, thoroughly efficient in operation both as to rapidity in washing, and sanitary and sterilizing in function, and within the price range of the average potential user.

One of the most important goals in dishwashing devices is the use of fresh water and detergent every time a fresh batch of dishes is being washed. Continuous use of the same water and detergent soon renders same unsanitary and actually a menace to health. The human element cannot be depended on to change water when it needs changing and for that reason my device is so designed as to automatically provide for use of fresh liquid and detergent every time a new tray of dishes is being washed.

In the design of my dishwasher I have kept moving elements to a minimum, have eliminated use of electrical devices and have employed the properties inherent in the force provided by flowing water at normal city water pressures to actuate a rotating jet member, to time the period of washing, and to actuate various valves for detergent supply and the draining procedure.

To provide for economy in use of water and detergent I have so designed my dishwasher that the initial period of washing includes a mixture of hot water and detergent which, after its jet action, gravitates to a reservoir from which it is picked up by special heads on the jet member, and is mixed with fresh liquid to weaken the detergent solution until the final period of washing is done by liquid of very little detergent content.

Keeping the general objective and function of my dishwasher in mind it is one of the primary objects of my invention to provide in a dishwasher of the class described, a chamber for receiving a basket of dishes, a rotatable jet member in the lower portion of the chamber adapted to direct streams of liquid against the dishes, rotation of said jet member being effected by the pressure of the liquid being discharged therefrom.

Another object of the invention is to provide an automatic timing valve which is manually set into operation to start the flow of liquid but which will close automatically after a predetermined period of time.

2

It is another object of the invention to provide adjusting means for setting the valve mechanism for a predetermined closing time to vary the length of washing time.

5 And another object of the invention is the provision of a detergent supply and related chambers and valves automatically controlled by the flow of liquid whereby a predetermined quantity of detergent will be mixed with the liquid on each cycle of operation of the device.

10 A further object of the invention is to inject the detergent upon the initial flow of fresh liquid so that the first washing will be with a strong detergent action with further washings becoming weaker in detergent strength.

15 One further object is to provide a transparent container for the detergent which renders same visible, whereby the supply of detergent may be replenished before it is depleted, minimizing the possibility of operating the dishwasher without detergent.

20 And a further object of the invention is the provision of a reservoir below the washing chamber to receive the gravitating liquid from the jets and dishes, said reservoir having an adjustable overflow permitting retention of a certain quantity of liquid in the reservoir and automatic means for draining the reservoir upon completion of the washing cycle.

25 30 And one more object of the invention is to provide a jet member having arms of different lengths each carrying a jet nozzle head, the different length arms providing means for spacing the heads in equidistant circular paths.

35 And another object of the invention is the provision of jet nozzle heads positioned at a predetermined depth in a supply of liquid in the reservoir, said heads being so constructed as to provide for mixture and discharge of air, liquid from the reservoir, and fresh liquid.

40 45 It is another object of the invention to provide a reservoir with the bottom sloping downwardly toward the center and with circumferential ribs whereby centrifugal action of the jet member will not cause outward movement of the liquid and starving of some of the jet nozzle heads.

50 One more object of the invention is to provide in the jet member pivot support, a ball bearing arrangement which will eliminate all friction of flat surface upon flat surface, the entire load of the jet member being carried by the ball bearing due to the force exerted upwardly by the pressure of the fresh liquid supply.

And still another object of the invention is to provide in an automatic liquid flow control de-

vice, a piston valve, normally spring-urged into closed position, another valve normally urged into closed position by the pressure of the liquid which is equalized on both sides of the piston of the first-mentioned valve, manual means for opening the second-mentioned valve to relieve the pressure on one side of the piston valve whereby the spring will be overcome by the pressure on the other side of the piston valve causing it to open for free passage of liquid, full length movement of the first-mentioned piston valve closing by positive contact the second-mentioned valve whereupon the first-mentioned valve will slowly close as the pressure is built up behind it.

Another object of the invention is to provide in a dishwasher of the class described a detergent supply source, a detergent chamber just below the supply source, a normally closed valve between the supply source and the detergent chamber, a mixing chamber below the detergent chamber, a normally open valve between the detergent chamber and the mixing chamber, the second-mentioned valve being operable by the pressure of the fresh liquid, closing of the second-mentioned valve causing opening of the first-mentioned valve to fill the detergent chamber with detergent, removal of pressure of the fresh liquid against the second-mentioned valve permitting it to drop, closing the first-mentioned valve and letting the detergent gravitate into the fresh liquid conduit where it will remain until the next washing cycle is started.

And still another object is to so arrange the detergent source and the detergent valving means that the valving operation will cause agitation of the detergent by air bubbles.

One more object of the invention is to provide in the washing chamber, supports for the dish basket and side guides to retain the basket in proper position for washing, said side guides being so constructed and arranged to act as deflectors for the streams of liquid discharging from the jets, and to add strength to the cabinet.

And still one more object of the invention is to provide sectional doors to the washing chamber which can be raised and lowered easily, which overlap sufficiently on each other and at the top and bottom of the chamber to prevent leakage of the washing liquid, and which have baffles adjacent overlapping portions for shielding against the liquid.

The dishwasher can be broken down into the following components; namely, the cabinet with its doors and removable top, the basket for the dishes and its supports, basket guides and liquid deflectors, the jet member with its special jet heads and nozzles, the reservoir in which the jet member rotates and the special drain therefrom, the fresh liquid valve control mechanism, and the detergent supply and valving and mixing arrangement.

Further objects and advantages as well as the construction and operation of my invention will be better understood by reference to the following description in connection with the accompanying drawings in which:

Fig. 1 is a side elevational view of the dishwashing machine with parts being broken away to better illustrate certain other parts.

Fig. 2 is an enlarged fragmentary cross-sectional view through an upper corner of the cabinet and door assembly.

Fig. 3 is a similar view through a basket support, guide and liquid deflector.

Fig. 4 is a top plan view of the dishwasher with the sides and cover removed to show the reservoir, the jet member and the basket supports.

Fig. 5 is an enlarged, fragmentary, detailed cross-section on the line 5-5 of Fig. 4, through the reservoir, jet member and drain.

Fig. 6 is a similar view through one of the jet heads on the line 6-6 in Fig. 5.

Fig. 7 is a similar view through the reservoir drain, the control valve for the fresh liquid supply and the detergent supply means.

Fig. 8 is an enlarged, fragmentary elevational view of the control valve and the operator's foot pedal for manually placing same in operation.

Fig. 9 is a similar view in a larger scale of a portion of the timing control mechanism shown in Fig. 7, parts being shown in elevation and section for clarity.

Referring now to the drawings by numerals of reference 1 is a rectangular frame or platform having suitable legs 2 which may be provided with leveling adjustment screws 3. A cabinet 4 may rest around the inner edge of the frame 1 to form the washing chamber 5. A suitable top 6 may be provided and may be removable.

Two opposite sides of the cabinet are normally closed by telescoping doors 7, suitably guided at the sides by guides 8, the doors having hooked portions 9 and 9' overlapping each other for raising of the doors to closed position. Hook portion 10 is provided at the top of the upper door member and is adapted to catch on lip 11 provided on top 6. Suitable handles 12 may be provided and a liquid deflector 13 may be positioned adjacent the overlapping portions 10 and 11 to eliminate leakage of water at that point. Drip member 14 catches any accumulations of moisture about the handle 12 when the doors are in open position, the moisture passing to the interior of the cabinet through opening 15. Lip 14' also serves to deflect drippings of moisture back into the cabinet.

Removably carried by the frame 1 are basket supports 16 which extend upwardly from the frame and slightly inwardly from the sides of the cabinet. The basket 17 rests on the supports 16 and is kept centered thereon by the angular guides 18 which are formed on and reinforce the side walls of the cabinet 4. Guides 18 also serve as liquid deflectors as will be hereinafter explained.

Concentrically located on frame 1 is a circular reservoir 19, the floor 20 of which inclines downwardly and inwardly toward the center. Spaced about the perimeter of the reservoir and extending inwardly are a plurality of ribs or deflectors 21 which break up the circular movement or whirling of liquid in the reservoir.

In one corner of the reservoir and frame is a sump 22 with upstanding overflow member 23 carrying a sleeved adjustable overflow ring 24, raising or lowering of which will govern the level of the liquid 25 in the reservoir.

A drain opening 26 is provided in the bottom of the sump and a screen 27 is positioned in the sump and spaced from the sump floor by projections 28.

Centrally located in the reservoir is the inlet opening 29 to which is connected the conduit 30. Mounted in the opening 29 is the hollow shaft 31 terminating at its upper end in a reduced shaft section 32. Openings 33 from the hollow shaft 31 connect with the chamber 34 formed

in the hub 35, a circular screen 36 positioned in chamber 34. The hub 35 is rotatably mounted on shaft 31 and has a threaded cap 37 which is rotatably positioned on reduced shaft 32 and carries a ball bearing 38.

Nut 39 threadedly engaging reduced shaft 32, bears against ball bearing 38 and holds the entire assembly in proper rotatable position. A protective cap 40 presses down over threaded cap 37 and covers the nut and ball bearing to prevent entrance of moisture thereto.

The hub 35 has a plurality of threaded openings 41 in each of which is carried a hollow arm 42 at the end of which is a jet head 43. As will be noted in Fig. 4 each of the arms is of a different length so that the jet heads will travel in different orbits as shown. This will provide jet washing coverage over a large area in the chamber.

Central chamber 44 of the jet head 43 opens to the hollow arm 42, the end of chamber 44 being plugged by suitable cap 45. Chamber 44 is surrounded by a chamber 46 preferably eccentrically related to chamber 44 and having a wall 47 to break the continuity of chamber 46. A portion of the outer wall of the eccentric chamber is formed of a screen 48.

Leading from chamber 44 is a small jet tip 49 which is in direct alignment with a larger jet nozzle 50 leading from the eccentric chamber 46 and shaped to provide a Venturi effect. The small jet is flared as shown.

To balance the jet member with its arms of different lengths I contemplate employing one of several methods or a combination of both. The jet heads may be made of different materials or the caps 45 may be of different weights to act as counterbalance elements.

It will be noted that the jet heads can be moved in either direction about the arms to change the angle of the jet and consequent speed of rotation of the jet member, the depth of the liquid in the reservoir also affecting the rotating speed of the jet member.

For ease in cleaning and repairing, the entire jet member can be removed quickly and expeditiously by removal of protective cap 40 and nut 39, the jet member then being lifted vertically from its rotative position on shaft 31.

The automatic control for the liquid supply comprises a valve chamber 51 one end of which is adjacent the drain chamber 52 and the other end of which is adjacent a detergent mixing chamber 53. The fresh liquid supply conduit 54 leads into the valve chamber 51 near the detergent mixing chamber end, a port opening 55 being provided between the valve chamber and the detergent mixing chamber.

The valve chamber 51 is in the form of a cylinder and carries therein a piston valve 56 with resilient packing ring 57. A bleeder opening 58 with circumferential groove 59 and screen 60 are provided on the piston for the purpose hereinafter specified. The end of the piston 56 is adapted to seat against the resilient insert 61 positioned adjacent the opening 55. A compression spring 62 seats against one end of the valve chamber 51 and against the valve seat end of the piston 56.

At the end of the chamber 51 opposite port opening 55 is valve seat 63 carried in the wall of the drain chamber 52, a valve 64 being adapted to rest against the seat 63 to prevent flow of liquid from the chamber 51 to the drain chamber 52.

The timing adjustment for the flow of liquid includes a stem 65 which passes through the drain chamber 52, having a loose fit where it passes through the valve seat 63, the exposed end 5 being supplied with a knurled knob 66 for adjustment purposes as will be hereinafter described.

The valve 64, when under pressure, is seated and cannot normally be turned. It is carried by the spool end 67 of sleeve 67, securely held to the stem 65 by sealing member 68 and collar 68'. Threaded end 65' of stem 65 engages tube 69 which is slidably but non-rotatably related to sleeve 67 by means of tip 69' moving in longitudinal slot 70, ring 70' forming a stop member to prevent disengagement of the tube from the threaded portion of stem 65. To prevent leakage about the stem 65 where it passes through the wall of the drain chamber 52, I have provided a packing gland 71 with sealing element 71'.

A foot pedal 72 is pivoted at 73, offset arm 74 abutting the knurled knob 66 for actuation of the control valve stem 65.

The detergent mixing chamber 53 exceeds preferably vertically as shown with a central dividing wall 75 causing the fresh liquid to flow upwardly over the wall and then downwardly as shown by arrows to quickly mix the detergent with the first flow of liquid.

The upper end of the detergent mixing chamber terminates with end wall 76 in which is located a valve 77 the lower end of which may be weighted to normally gravitate to open position as shown. The valve 77 has a central opening 78 extending part of the way down from the top and connecting with sidewardly extending openings 79 below which is located a valve sealing ring 80 adapted to seat against valve insert 81 when the valve is moved to closed position.

Above the detergent mixing chamber is located a detergent measuring chamber 82, a suitable detergent container 83 being adapted to seat in inverted position above the chamber 82, and held in seated position by clamp 83'. The container 83 receives a special valve cap 84 with ball valve 85 and strainer cage 86. The ball valve 85 is in alignment with the valve 77 and is adapted to be contacted and opened thereby, permitting a supply of detergent to flow down into and fill the detergent measuring chamber 82, the valve 77 between said chamber 82 and the detergent mixing chamber being closed.

A pressure conduit 87 leads from the detergent mixing chamber to the drain valve pressure chamber 88 adjacent the drain chamber 52, a valve 89 being operatively located in the wall of pressure chamber 88 and in alignment with the drain opening 25 in the bottom of sump 22, the flange 90 adapted to seat around said opening to seal same and also to seat the resilient ring 91 against the upper wall of the chamber 88.

A waste pipe 92 leads from the drain chamber 52 and may be connected to the waste line of the building in which the dishwashing machine is installed.

Operation

The first phase, prior to operation is the installation of the dishwashing machine. It will be seen that the device is small and compact and can be installed under a counter or in some such suitable location, it being necessary to connect up the hot water supply conduit 54 and drain or waste pipe 92 to waste line of the building.

A suitable supply of detergent can be placed in container 83. It can be mentioned here that a sterilizing liquid is but one of many substances

which can be added to the detergent or used separately in container 83 which is inverted over the detergent measuring chamber 82 after cap 84 with its ball valve 85 and ball cage 86 has been applied to said container. Some of the 5 detergent may be poured into the chamber 82 for the initial starting of the process. However, this is not necessary after the first time.

When the machine is not operating the valves 71 and 89 are open. The valve 64 and piston valve 56 are closed and there is fresh liquid under normal pressure in conduit 54 and in valve chamber 51 having passed through bleeder opening 58, the pressure of the liquid plus the action of the spring normally urging the piston 56 into port (55) closing position. A predetermined quantity of detergent is lying at the bottom of conduit 30 preparatory to mixing with fresh liquid.

The next step is the placing of the dishes into the machine. They are first placed into the basket 17, the doors 1 are dropped down and the basket slid into place on supports 16 and guided by angular members 18. The doors are then closed and the operator steps down on foot pedal 72 and then removes his foot. Control valve stem 65 will be forced inwardly, valve 64 will be unseated permitting liquid under pressure in valve chamber or cylinder 51 to pass out through valve seat 63 into drain chamber 52 and down the waste pipe 92. At this time the pressure on both sides of the piston 56 will be unbalanced and the pressure exerted by the fresh liquid supply coming through conduit 54 will overcome the compression spring 62 and force the piston away from the opening 55 permitting the fresh liquid to pass through said opening.

The movement of the piston 56 in either direction is not a rapid one but is timed by the passing of the liquid through valve seat 63 and port 58. When the piston has moved a predetermined distance to the left the piston end wall contacts the tube 69 and forces the valve 64 toward its seat to close the passage through the valve seat 63 around the loose fitting valve stem. When the liquid flow into chamber 52 is stopped the liquid continues to reach chamber 51 through port 58 and as the pressure gradually builds up the piston 56 is moved to the right to close port 55 stopping the flow of fresh liquid.

Adjustment of the period of fresh liquid flow is obtained by turning knurled knob 66 in one direction or the other causing the threaded stem 65 to move the tube 69 either inwardly or outwardly in sleeve 67 to change the distance between the end of tube 69 and the piston wall 56.

When the foot pedal is depressed and the fresh liquid starts flowing it passes upwardly in detergent mixing chamber 53 over the central dividing wall 75 and down into conduit 30. The building up of the pressure of the liquid in chamber 53 causes valve 71 to raise, closing openings 78 and 79, the top of said valve 71 contacting ball valve 85 to open same. At this time detergent will flow down into detergent measuring chamber 82 filling same. Air bubbles will flow up through the detergent to cause agitation thereof.

The liquid under pressure in chamber 53 also passes through small conduit 87 to drain valve pressure chamber 88 forcing drain valve 89 upward into position closing drain opening 26.

The hot fresh liquid mixed with a detergent passes up through conduit 30 and out openings 33 into hollow arms 42 and out through small jet tips 49 and larger jet nozzles 50. The nozzles 75

may be set at any angle desired and the force of the liquid being ejected therefrom will cause the entire jet assembly to rotate. The speed of rotation may be varied by changing the angle of the jet heads. The depth of the liquid in the reservoir 19 will also affect the speed of rotation of the jet assembly.

It will be seen in Fig. 4 that the length of arms 42 are all different, spacing the heads 43 in concentric equidistant paths to give a broader jet coverage. The use of Venturi jets and the mixing with air will give a greater force and volume to the amount of fresh liquid supplied.

At the start of each washing cycle the reservoir 19 is free of liquid. However, upon the initial flow of fresh liquid and the closing of the drain valve 89 the mixture of liquid and detergent gravitating from the dishes and jets will accumulate in the reservoir to a depth determined by the setting of adjustable overflow 24. The force of the fresh liquid passing through the jet heads 43 will now pick up a mixture of liquid and air from the reservoir as shown in Fig. 6.

It is only the initial short period of fresh liquid supply which has a high concentration of detergent, continued flow of fresh liquid being free of detergent but picking up a gradually weakening solution from the reservoir. As the flow of fresh liquid continues and mixes with the liquid from the reservoir the detergent content decreases until the dishes are being rinsed with practically clear liquid.

When the flow of liquid stops by the closing of port 55, pressure is relieved on drain valve 89 which opens to completely drain the reservoir; the valve 71 is opened permitting a charge of detergent to gravitate into the detergent mixing chamber 53 awaiting the next washing cycle.

The basket of dishes may now be removed or they may be rewashed as many times as desired, the normal washing period found by actual test to be from thirty seconds to a minute and a half, depending on the adjustment of the automatic liquid control mechanism. However, this period may be whatever is found desirable and is limited only by the range of the automatic liquid control mechanism. After removal of the dishes the machine itself can be washed out by the same operation with or without detergent although it has been found that the machine is cleaned each time the dishes are washed and that further washing of the machine is not necessary.

Where the city water pressure is low it has been found that the machine will operate for a longer period to compensate for the lack of pressure. This is because it takes longer for the piston 56 to act under lower pressure. Also, where conditions of low water pressure are encountered a booster pump or other suitable auxiliary pressure boosting means may be employed, preferably connected to the supply line to increase the pressure of the liquid therein. A pressure switch operated by the liquid pressure in the detergent chamber 53 will provide for automatic control of the electric booster pump or other booster means.

From the preceding specifications it will be seen that I have provided a dishwashing machine which is relatively simple in construction and operation and which can be installed under the counter in a convenient and out of the way place. A washing and rinsing with clear fresh liquid and detergent is provided during each washing cycle and soiled water is not continuously used. The jet member is rotated by the

force of the liquid discharging therefrom and the jet heads are designed to pick up liquid from a reservoir below the washing chamber at a ratio of one part of fresh liquid to five parts reservoir liquid; the concentration of detergent gradually diminishing during the washing cycle.

The device is manually set into operation to start the washing cycle which continues thereafter automatically; closing of drain and detergent valves and operation of the liquid flow control mechanism and the rotation of the sprays being automatic.

With each of the jet heads rotating in a different orbit a wide coverage of washing is obtained so that liquid will reach all sides of the articles in the basket.

It is obvious that many changes may be made in form, proportion and details of construction without departing from the spirit of my invention and I reserve all rights to such changes as come within the scope of the preceding specifications and claims which follow.

At the start of each washing cycle there is no liquid in the reservoir. Consequently, the discharge of fresh liquid from the jet member will cause the jet member to rotate at high speed until the supply of liquid in the reservoir builds up to a level where the jet heads begin picking up liquid from the reservoir. This slows down the speed of rotation of the jet member but not the force of the jet discharging from each head.

What I claim as new and desire to secure by Letters-Patent is:

1. In a dishwashing device of the class described, a washing chamber, means for positioning articles to be washed in the chamber, a liquid reservoir at the bottom of the chamber, a jet member in the chamber below the articles to be washed, portions of said jet member being immersed in the liquid reservoir and portions of said jet member extending above the liquid in the liquid reservoir, means for supplying fresh liquid under pressure to the jet member, inclined jets on the jet member, said jet member being rotatable by the force of the liquid discharging from the inclined jets, means for supplying liquid from the reservoir to the jet member for mixing with the fresh liquid and discharge from said jet member.

2. In a dishwashing device of the class described, a washing chamber, means for positioning articles to be washed in the chamber, a liquid reservoir at the bottom of the chamber, a jet member in the chamber below the articles to be washed, portions of said jet member being immersed in the liquid reservoir and portions of said jet member extending above the liquid in the liquid reservoir, means for supplying fresh liquid under pressure to the jet member, inclined jets on the jet member, said jet member being rotatable at high speed by the force of the initial supply of fresh liquid discharging from the inclined jets, means for supplying liquid from the reservoir to the jet member for mixing with the fresh liquid and discharge from the jet member, means including the liquid in the reservoir for slowing down the speed of rotation of the jet member as the level of said reservoir liquid increases.

3. In a dishwashing device of the class described, a washing chamber, means for positioning articles to be washed in the chamber, a liquid reservoir at the bottom of the chamber, a jet member in the chamber below the articles to be washed, portions of said jet member being im-

mersed in the liquid reservoir and portions of said jet member extending above the liquid in the liquid reservoir, means for supplying fresh liquid under pressure to the jet member, inclined jets on the jet member, said jet member being rotatable by the force of the liquid discharging from the inclined jets, intake openings in said jet member below the surface of the liquid in the reservoir for receiving liquid therefrom to be mixed with the fresh liquid and directed by the jet member against the articles to be washed.

4. The structure as specified in claim 1, means for maintaining the liquid in the reservoir at a predetermined level for desired operation of the jet member, said means for supplying liquid from said reservoir comprising an inlet adjacent the bottom of said jet member, a portion of said inlet being submerged in the liquid supply in the reservoir whereby air and liquid will be simultaneously supplied to the jet member.

5. The structure as specified in claim 1, and an adjustable overflow from the liquid reservoir to maintain the liquid therein at a predetermined level for desired operation of the jet member.

6. The structure as specified in claim 1, said jet member comprising a plurality of hollow arms, each carrying a jet head at the end thereof, a chamber in the jet head connecting with the hollow arm, a discharge jet opening from the chamber, the inclined jets on the jet members being in alignment with the discharge jet opening.

7. The structure as specified in claim 1, said jet member comprising a plurality of hollow arms, jet heads for use on said arms including a chamber connecting with the hollow arm, a secondary chamber in the jet head, a discharge jet opening between the two chambers, a jet nozzle on the head having one end opening to the secondary chamber and aligned with the discharge jet opening, said means for supplying liquid from said reservoir comprising an air and liquid intake opening from the lower portion of the secondary chamber, a portion of said last-named opening being immersible in liquid in the reservoir, whereby the force of the liquid passing through the discharge jet opening between the two chambers will draw liquid from the reservoir and air from above the liquid into the secondary chamber for mixing and discharge out through the jet nozzle.

8. The structure as specified in claim 1, said jet member comprising a plurality of hollow arms, jet heads for use on said arms, a central chamber in each of the heads, the hollow arm opening into said central chamber, a secondary chamber partially surrounding the central chamber and eccentrically related thereto, a discharge jet opening between the central chamber and the secondary chamber, a jet nozzle leading from the secondary chamber and aligned with the discharge jet opening, said means for supplying liquid from said reservoir comprising a screened opening at the lower end of the secondary chamber, said screened opening being partially immersible in the liquid in the reservoir, whereby the force of the liquid passing through the discharge opening between the two chambers will draw liquid from the reservoir and air from above the liquid into the secondary chamber for mixing and discharge through the jet nozzle.

9. In a dishwashing device of the class described, a washing chamber, means for positioning articles to be washed in the chamber, a liquid reservoir at the bottom of the chamber, a jet

member in the chamber below the articles to be washed, portions of said jet member being immersed in the liquid reservoir and portions of said jet member extending above the liquid in the liquid reservoir, means for supplying a predetermined quantity of fresh liquid under pressure to the jet member, inclined jets on the jet member, said jet member being rotatable by the force of the liquid discharging from the inclined jets, means for supplying liquid from the reservoir to the jet member for mixing with the fresh liquid and discharge from said jet member.

10. In a dishwashing device of the class described, a washing chamber, means for positioning articles to be washed in the chamber, a jet member in the chamber below the articles to be washed, jet heads on the jet member, means for supplying fresh liquid to the jet member, said jet heads being partially immersed in the liquid in the reservoir, an inlet in each jet head to receive liquid from the reservoir, a second inlet in each jet head to receive fresh liquid from the fresh liquid supply, and a discharge jet nozzle on each jet head to discharge the fresh liquid and the liquid received from the reservoir.

11. In a dishwashing device of the class described, a liquid reservoir and a jet member, jet heads on the jet member, each jet head including a fresh liquid chamber, a second chamber, an inlet in the second chamber, said inlet being immersible in the liquid in the reservoir, an outlet from the fresh liquid chamber, a discharge jet nozzle from the second chamber in alignment with the outlet from the fresh liquid chamber, the

force of the liquid discharging from the fresh liquid chamber drawing liquid from the reservoir through the inlet and discharging a mixture of fresh and reservoir liquid from the discharge nozzle.
